UNITED STATES PATENT OFFICE.

SAMUEL EARL GARD, OF AMLIN, OHIO.

SAFETY-RAZOR.

1,310,333.

Specification of Letters Patent. Patented July 15, 1919.

Application filed August 29, 1918. Serial No. 251,975.

To all whom it may concern:

Be it known that I, SAMUEL E. GARD, a citizen of the United States, residing at Amlin, in the county of Franklin and State 5 of Ohio, have invented certain new and useful Improvements in Safety-Razors, of which the following is a specification.

This invention relates to cutlery, and more particularly to that class of implements called safety razors.

The invention has for its primary object the provision of a device of the character described, which is exceedingly simple in construction, thereby enabling the same to 15 be manufactured at a minimum cost, and which is strong and durable in use, and highly efficient for the purpose designed.

Another object of the invention is to provide a safety razor, whereby the razor blade 20 may be readily positioned within the holder for the desired operation, and when the same is completed, may be easily removed, the various constituent parts disassembled, and made ready for cleansing whereupon 25 the same may be adapted for subsequent usage.

I have illustrated the above mentioned embodiment of the invention in the accompanying drawings forming a part hereof, 30 and improved details in the construction and arrangement of parts will be apparent from an inspection of such drawings, in connection with specific description hereinafter contained.

35 In the drawings:—

Figure 1 is a side elevation of the device; Fig. 2 is a top plan of the blade holding means;

Fig. 3 is a transverse section of the blade 40 holding means, and showing the manner whereby said means are connected with the handle.

Referring now to the drawings, wherein like reference characters designate like or 45 corresponding parts throughout the several views, the numeral 1 represents a handle having a slightly deflected shank 2, threaded as at 3 and adapted to have turned into engagement therewith a thumb nut designated at 4, while the upper end of said shank portion is provided with an enlarged head 5. The holder comprises a base plate 6 which is provided across its rear edge with an upstanding flange 7, while the forward edge of the same is provided with the

usual guard comprising comb-like structure, 8, commonly known to this art. The sides of the blade holder 6 are raised, as shown at 9, and have formed thereon engaging pins 10 and 11, which pins pivotally support the blade clamp. This comprises a jaw 13 having legs 14 and 15 provided with suitable openings, as at 16, for receiving the pins 10 and 11 and thereby serving as means whereby the jaw 13 may 60 be pivotally supported upon the blade holder. The rear ends of the legs 14 and 15 of the clamping member are provided with angularly disposed or inturned feet 17 and 18 normally engaged by a leaf spring 19, the 70 spring in turn being centrally secured to the upstanding flange 7 by suitable fastening devices, such as rivets or the like, as designated at 20.

The base plate 6 of the blade holder has 75 therein a slot 21, enlarged at its forward end to permit the introduction of the enlarged head 5 of the shank 2, while the remaining length of the slot is of such width as to snugly receive the shank 2, consequently serving as efficient means for connecting the handle portion to the holder. The blade holder may be provided with the usual bosses, or stops, 22, upon the guard portion 8, which stops serve as means for 80 limiting the forward movement of the blade 23.

In assembling the device, it will be apparent that the head 5 is inserted within the slot 21 of the holder 6. The thumb 90 nut 4 is then adjusted into engagement with the holder 6, thus serving as efficient means for insuring the positive connection between the blade holder and the handle. The clamp is then swung back upon its pivot 95 pins 10 and 11 against the tension of the spring 19 into an out of the way position, whereupon the blade 23 is laid upon the side members 9 of the holder 6 having been previously adjusted into engagement with 100 the stops 22, the clamp 12 is then swung forwardly and downwardly into engagement with the blade 23 whereupon said blade will be firmly clamped upon the holder 6. It will be noted that the spring provides for 105 the necessary clamping tension, thus preventing the longitudinal movement of the blade within the holder.

Still further embodiments of the invention than those herein especially defined may 110

be resorted to such as conditions or preferences may dictate and as may be in keeping with the hereto appended claim.

I claim:

- 5 In a safety razor, the combination with a handle, a blade holder carried thereby and having a guard at its front, an upturned flange at its rear, and upturned sides, and a razor blade overlying said sides and guard;
- 10 of a clamp comprising a jaw overlying the blade and legs projecting rearward there-

from and having inturned feet, pivots between said legs and the sides of the clamp, and a leaf spring secured at its center to said upturned flange and with its ends overlying said inturned feet, as described. 15

In testimony whereof I affix my signature in presence of two witnesses.

SAMUEL EARL GARD.
